FIG. 1.

FIG. 2.

FIG. 3.

FIG. 4.

FIG. 5.

FIG. 6.

FIG. 7.

FIG. 8.

FIG. 1 is a plan view of an oral hygiene tool embodying my new design;

FIG. 2 is a front elevation of the tool shown in FIG. 1;

FIGS. 3 and 4 are respectively lefthand and righthand end elevations of the tool shown in FIGS. 1 and 2; and

FIGS. 5, 6, 7 and 8 are local sectional views taken on the lines 5—5, 6—6, 7—7 and 8—8 of the FIG. 2 showing the conformation of the scraper portion of the tool.

In bottom plan the tool has an outline identical to the outline shown in the top plan view of FIG. 1, and the rear elevation of the device is complementary to the front elevation shown in FIG. 2.

I claim:

The ornamental design for an oral hygiene tool, substantially as shown and described.
